UNITED STATES PATENT OFFICE.

JAMES HENRY MULL, OF PHILADELPHIA, PENNSYLVANIA, ASSIGNOR TO CHICAGO PNEUMATIC TOOL COMPANY, OF CHICAGO, ILLINOIS, A CORPORATION OF NEW JERSEY.

PIPE-BENDING MACHINE.

No. 811,516.

Specification of Letters Patent.

Patented Jan. 30, 1906.

Application filed April 22, 1905. Serial No. 256,841.

To all whom it may concern:

Be it known that I, JAMES HENRY MULL, a citizen of the United States, residing in the city and county of Philadelphia, State of Pennsylvania, have invented a new and useful Pipe-Bending Machine, of which the following is a specification.

My invention consists of a novel construction of a pipe-bending machine which can be cheaply manufactured, is powerful and efficient in its operation and not liable to easily get out of order, and wherein different sizes of pipe or other material can be readily and expeditiously bent or coiled without requiring the services of skilled labor.

It also consists of a novel construction of an adjustable plate which can be readily adjusted and locked in any desired position for the purpose of bending different sizes of pipe or of bending the pipe or other material into different curvatures.

It further consists of a novel construction of sliding abutment which is adjustably mounted in the grooved adjustable plate, whereby the machine can be quickly adapted to bend pipe of various sizes into the desired curvatures.

It further consists of novel means carried by a sliding abutment whereby different sizes of pipe can be bent into different curvatures without the liability of flattening the pipe during the act of bending.

It further consists of a novel construction of adjustable or interchangeable bending-dies which are readily shifted into operative position, whereby different sizes of pipe may be bent into different curvatures, according to requirements.

It further consists of other novel features, all as will be hereinafter fully set forth, and pointed out in the claims.

Figure 1 represents a side elevation of a pipe-bending machine embodying my invention. Fig. 2 represents a top plan view of Fig. 1. Fig. 3 represents a partial section on line *x* *x*, Fig. 1. Fig. 4 represents a partial section on line *y* *y*, Fig. 1, certain of the parts being omitted for the sake of clearness of illustration. Fig. 5 represents a perspective view of the sliding abutment and its adjuncts in detached position.

Similar numerals of reference indicate corresponding parts in the figures.

Referring to the drawings, 1 designates my novel pipe-bending machine, the same comprising the post or standard 2, having the collar 3 thereon, above which extends the upper portion 4, which serves as a support for the block or carrier 5, which is held in position by means of the cap 6, which is secured to the carrier by the bolts or other fastening devices 7.

8 designates a pinion which is mounted on the bearing or stud 9, which is provided with the flange 10, which is secured to the carrier by means of the bolts 11 or other fastening devices, said pinion meshing with the quadrant-gear 12, which is mounted on the shaft 13, which rotates in the bearing 14, mounted on the carrier 5. The outer extremity of the shaft 13 has mounted thereon a plurality of bending-dies 15, 16, and 17, which are shown as successively inclosed, are preferably quadrant-shaped, as will be understood from Fig. 1, and are provided with the grooves 18 for the reception therein of the pipe to be bent.

19 designates a keeper which is adapted to be secured to a suitable portion of the periphery of the bending-dies by means of the bolt 20 or other suitable fastening device, the office of said keeper being to secure temporarily in position the end of the pipe which is being bent. In order to enable the desired form of bending-die 15, 16, or 17 to be readily employed or rendered inoperative at will, I employ the key or spline 21, which is adapted to engage a keyway common to the shaft 13 and each of the bending-dies, it being apparent that when the key 21 is driven into its extreme position only the inner or larger bending-die 17 can be used. When it is desired to render, for example, the larger bending-die 17 inoperative, the key 21 is withdrawn to the point indicated in Fig. 4, whereupon the larger die 17 can drop into the position indicated in dotted lines and the die 16 is then in operative position. Similarly, to render the die 15 operative the key 21 is withdrawn sufficiently to permit the dies 17 and 16 to drop to their lowest position, whereupon the die 15 becomes operative, it being understood that each of the bending-dies are held in the

desired position by means of set-screws or other similar devices and that the downward movement of said bending device may be limited by means of a suitable stop, as 22 or 5 its equivalent.

In order to dispense with the apertured plate heretofore employed in devices of this general character and to render the machine more easily adjusted to different sizes and 10 varieties of pipe, I employ the rotatable adjustable face-plate 23, having in its outer portion the longitudinally-extending ways or groove 24, said plate being swiveled or mounted upon the pin 25 as an axis and being guided and locked in position by means 15 of the engagement of the head 26 of the bolt 27, which passes through the curved groove or ways 28 in the carrier 5.

29 designates a sliding abutment, consisting 20 of a plate having passed therethrough the bolt 30, the head 31 of which slides in the groove or ways 24, while the nut 32 can be tightened or loosened so as to lock the sliding abutment 29 in the desired position, according 25 to requirements.

33 designates a roller mounted on the stem 34, which terminates in the head 35, which also travels in the ways 24.

36 designates the guide-pin, which passes 30 through the abutment 29 and has the head 37, which also travels in the ways 24.

38 designates the hand-wheel, by which the machine is operated according to requirements, the hub 39 of said hand-wheel being keyed, pinned, or otherwise secured to the pinion 8, so that said hand-wheel and pinion 35 rotate in unison.

40 designates the section of pipe or tubing in the act of being bent, the extremity 41 of 40 said tubing being held in position by the keeper 19.

The operation is as follows: To bend a section of pipe or tubing, as 40, the end 41 of the same is held in position by the keeper 19. 45 The straight or unbent portion of the pipe is in contact with the under side of the roller 33, and the operator having turned the hand-wheel 38, the pinion 8, and the quadrant-gear 12 in the proper direction, as indicated by the 50 arrow *a*, the parts will assume the position seen in Fig. 1. Upon loosening the keeper 19 the pipe can be readily removed, and in practice I find that the quadrant-gear 12, by reason of the position the parts assume, as 55 in Fig. 1, when the act of bending is completed, will, without attention from the operator, turn toward the left, so as to automatically drop into operative position.

It will be evident that the hand-wheel 38, 60 the pinion 8, the quadrant-gear 12, the shaft 13, and the bending-die 15, 16, or 17, as the case may be, will operate in unison. Upon loosening the nut 32 the abutment carrying the pin 36 and the roller 33 can be shifted

along the ways 24 of the plate 23, so as to adjust said abutment to the various sizes of pipe to be bent or to the desired size of bending-die which may be employed. By loosening the bolt 27 the plate 23 can be rocked on its axis 25, so as to carry the sliding abutment 70 into the desired position.

By the employment of the different-sized dies and my novel means for rendering the desired one of the same operative or inoperative I am enabled to adapt the machine to a 75 wide variety of uses, as is evident.

It will be apparent that my novel machine, while being of a very simple character, can accomplish a great variety of work and only requires the services of an ordinary 80 helper who can, without instruction, by the aid of the machine bend pipe or tubing to any desired complex curvature in a very short time. The machine being light in weight is readily carried from shop to job, or vice 85 versa, and can be secured to any column, stanchion, or any available support in a few minutes, or a suitable stand can be employed, as shown. I have found that piping of steel, iron, brass, copper, or other materials up to 90 two inches in diameter can be bent cold without any flattening of the pipe during bending. It is also well adapted for the use of special dies that can be readily attached for bending light angles, flats, or T-bars to any desired 95 radius as easily as bending pipe, and one operator can, without assistance, bend a piece of two-inch pipe to an S bend in three minutes.

It will be apparent that changes may be 100 made by those skilled in the art, which will come within the spirit of my invention, and I do not, therefore, desire to be limited in every instance to the exact construction herein shown and described.

Having thus described my invention, what I claim as new, and desire to secure by Letters Patent, is—

1. In a bending-machine, a bending-die, a support therefor, an angularly-adjustable rotatable face-plate having ways therein extending upon opposite sides of the axis of the face-plate, a sliding abutment mounted in said ways and means for actuating said die.

2. In a bending-machine, a bending-die, a support therefor, an angularly-adjustable rotatable plate having ways therein extending upon opposite sides of the axis of the face-plate, a sliding abutment mounted in said ways, a carrier for supporting said die and plate, and means for locking said plate with respect to said carrier.

3. In a bending-machine, a bending-die, a support therefor, an angularly-adjustable rotatable plate having ways therein extending upon opposite sides of the axis of the face-plate, a sliding abutment mounted in said ways, a carrier for supporting said die and

plate, and means for locking said plate with respect to said carrier, in combination with means for actuating said die.

4. In a bending-machine, a bending-die, a support therefor, an adjustable plate having ways therein, a sliding abutment mounted in said ways, a carrier for supporting said die and plate, a curved groove in said carrier, and locking devices common to said groove, and plate.

5. In a bending-machine, a bending-die, a carrier, a support therefor, an adjustable plate having a longitudinally - extending groove or ways therein, a sliding abutment supported in said groove, means for locking said abutment in position, a curved groove in said carrier, and locking devices common to said groove and plate.

6. In a bending-machine, a carrier, means for supporting said carrier, a shaft mounted in suitable bearings, a quadrant-gear mounted on said shaft, a bending-die mounted on said shaft, a rotatable plate supported by said carrier, means common to said carrier and plate for locking said plate in the desired position and a sliding abutment carried by said plate and movable to opposite sides of the axis of the plate.

7. In a bending-machine, a standard, a carrier mounted thereon, a shaft having bearings in said carrier, a plurality of independently-movable bending-dies carried by said shaft at the same time, and means for maintaining any of said dies in operative relation with said shaft at will.

8. In a bending-machine, a support, a shaft therein, a plurality of independently-movable bending-dies on said shaft at the same time and angularly movable to operative or inop-

erative positions, and means for maintaining any of said dies in operative position.

9. In a bending-machine, a support, a shaft therein, a plurality of independently-movable bending-dies of different diameters on said shaft at the same time, and means for maintaining operative connection of any of said dies with said shaft in substantially the same bending-plane.

10. In a bending-machine, a support, a shaft therein, a plurality of successively-in- closed bending-dies upon said shaft at the same time, and angularly movable with respect to it, and means for maintaining any of said dies in operative angular relation to said shaft at will.

11. In a bending-machine, a bending-die, a shaft on which said die is mounted, a quadrant-gear mounted on said shaft, a pinion meshing with said quadrant-gear, a hand-wheel whereby said pinion and gear may be rotated in unison, an angularly-adjustable face-plate and a sliding abutment mounted on said face-plate.

12. In a bending-machine, a bending-die, a shaft on which said die is mounted, a quadrant-gear mounted on said shaft, a pinion meshing with said quadrant-gear, a hand-wheel whereby said pinion and gear may be rotated in unison, an angularly-adjustable face-plate having ways therein, a sliding abutment mounted in said ways, means for locking said face-plate in position, and means for locking said abutment in position.
